UNITED STATES PATENT OFFICE.

EDWARD W. COOEY, OF HYDEPARK, MASSACHUSETTS.

ROTARY ENGINE.

SPECIFICATION forming part of Letters Patent No. 723,242, dated March 24, 1903.

Application filed September 13, 1902. Serial No. 123,308. (No model.)

To all whom it may concern:

Be it known that I, EDWARD W. COOEY, a citizen of the United States of America, residing at Hydepark, in the county of Norfolk 5 and State of Massachusetts, have invented certain new and useful Improvements in Rotary Engines, of which the following is a specification.

The invention relates to rotary engines, 10 more particularly to the steam-cylinders and pistons therefor of that class in which the pistons while revolving around the engine-shaft reciprocate in a direction parallel to the axis of the shaft instead of radially thereto, 15 as in the great majority of rotary engines; and the improvements consist in a cylinder having an annular steam-chamber with stationary sinuous side or end walls, a disk which is secured to the engine-shaft within this chamber 20 and which divides it into equal portions, the peripheral wall of which chamber is formed by a cylinder which is secured to or made integral with the periphery of the disk, also in pistons constructed to serve as steam- 25 valves and which reciprocate in radial slots in the disk and in directions parallel with the axis of the engine-shaft, and, further, in the construction of the hub of the engine-shaft by which it serves as a steam cut-off, in connection 30 with a valve which slides longitudinally over it, all of which will be understood from the following description, in connection with the accompanying drawings, wherein—

Figure 1 is a vertical longitudinal section 35 of the frame and outer casing of the engine, also of the end portions which form the sinuous walls of the steam-chamber and of the cylinder and outer portion of the disk of which the cylinder forms a part, while the engine-shaft and its hub are in elevation. Fig. 2 is 40 a vertical cross-section of the engine through the revolving disk on line 2 2, Fig. 1. Fig. 3 is a vertical cross-section on line 3 3, Fig. 1, through the portion of the engine-hub which 45 contains the steam-passages. Fig. 4 is an elevation of the end of the engine at the right of Fig. 1, showing the connections with the slide-valve and the lever by which it is operated. Fig. 5 is a greatly-enlarged plan view 50 of a portion of one of the pistons P viewed from the side toward the axis of the disk D. The lower or inner portion of one side of this

piston is cut away on line 5 5, Fig. 2, so as to show two of the upper steam-chambers therein. Fig. 6 is an enlarged end elevation of the 55 piston, showing the roller-packing. Fig. 7 is a side elevation of one end of the piston with its frame in section on line 7 7, Fig. 5. Fig. 8 is an enlarged detail of the cylinder D' in section on line 8 8, Fig. 9, to show the anti-friction ball-bearings for the upper tongue 60 of the piston. Fig. 9 is an enlarged plan view of the same bearings with the retaining-plate removed.

Referring to the drawings, A is the outer 65 cylindrical casing and frame of the engine; B B', the ends or heads of steam-chamber, the inner surfaces of which are the counterparts of one another and are so shaped as to form the sinuous annular steam-chamber C, 70 within which the disk D revolves, together with the pistons P, which reciprocate in that disk.

D' is a cylinder around the disk D, which may be integral therewith and constitute the 75 web of the cylinder, or it may be secured to its periphery. This cylinder forms the outer limit of the steam-chamber C.

Upon the engine-hub H, which is keyed to the shaft S, the disk or web D is mounted, 80 and it may be a part of the same casting as the hub. In Fig. 1 the diagonal dotted lines b² b² indicate the angle at which the inner faces of the heads B B' are made to form the sinuous chamber C for the passage of the 85 pistons P. As here shown these dotted lines represent the portions of heads upon the side of the hub H opposite the view point. The portions of the heads B B' upon the side from which the engine is here viewed are removed, 90 as heretofore stated. The engine here illustrated is provided with two pistons only; but three or more might be used with a proper arrangement of the steam-passages in the hub and disk D.

In the surface of the hub H beneath each piston P a groove h² is formed longitudinally of the hub and in the same radial plane. A groove d² is formed in the inner surface of the cylinder D', and tongues p' p² to fit the 100 respective grooves are formed upon the inner and outer edges of the pistons and guide and hold them in place when the disk D revolves and the pistons are caused to slide back and

forth in the slots in the disk by the pressure of their ends against the side walls of the chamber C. Each of these pistons is constructed with eight chambers—four in the upper or outer portion $n' n^2 n^3 n^4$, each of which has an opening at the end of the piston, as indicated in dotted lines, Fig. 1, and at the upper left-hand portion of Fig. 5, and four in the lower or inner portion $l' l^2 l^3 l^4$, each of which has an elongated opening along the lower side of the piston—that is, next the hub H, as indicated in the sectional view, Fig. 2, and in plan at the lower portion of Fig. 5. The elongated openings in the lower chambers $l' l^2 l^3 l^4$ register with steam-ports $e' e'$ in the bottom of the slots in the disk D which contain the pistons, and these ports e' open from steam-passages $f' f'$, which extend longitudinally through the hub H and into the smaller portion H' of the hub, which may be termed the "valve" portion.

The chambers in the pistons are connected by steam-passages, as follows: Lower l' is connected with upper n^4 , lower l^2 with upper n^3 , lower l^3 with upper n^2 , and lower l^4 with upper n' . It is not practicable to show all of the connecting passages in one view; but in Fig. 5 is illustrated the passages from l^2 to n^3 and from l^4 to n' . (Indicated by arrows.)

30 The pistons P have two packing-pieces p^3 at each end, which are hinged to sliding supports p^4 . These supports are constantly pressed outward by springs p^5 and the packing-pieces by springs p^6 . The pistons may also be provided with antifriction devices, such as steel rolls or balls d^3 , in endless passages d^4 along the sides of the ribs p^2 , as shown in Figs. 8 and 9, and these balls may be held in place by retaining-plates d^5 . Also the pistons may be provided with a roller p^7 at each end to reduce friction, as indicated in Figs. 5 and 6. These rollers may also be pressed outward by springs.

In the periphery of the portion H' of the hub, sections of spiral grooves $g g$ and $g' g'$ are cut. In the engine illustrated only two sliding pistons are employed, and therefore only two pairs of spiral-groove sections are needed. When three or more pistons are used, an additional pair of grooves for each should be made in the hub. Around this portion H' of the hub is a valve-ring V, adapted to slide longitudinally thereof. This ring is prevented from turning by ribs h^3 upon its periphery, which engage grooves a^2 upon the inside of the casing. (See Fig. 3.) Around the entire circumference of the ring V is an annular passage v' , and upon diametrically opposite sides thereof steam-ports $v^2 v^3$ are cut through the ring from the passage v' . The upper part of the port v^2 , which is in conjunction with the steam-inlet E, is extended longitudinally to nearly the full length of the ring V, so that some portion of that port will be open to the steam-inlet in whatever position the sliding valve-ring may be. The an-

nular chamber O, between the hub portion H' and the casing A', is nearly double the length of the valve-ring V, and diametrically opposite the steam-inlet E a branched exhaust-port I opens from each end of the chamber O.

The two pairs of spirally-cut grooves $g g'$ are located in such positions in relation to one another that the steam-ports $v^2 v^3$ of the valve V can admit steam to one pair only of those grooves at the same time and that when the ports $v^2 v^3$ are open to one pair of said spiral grooves the other pair of grooves are open to the portion of the chamber O which is beyond the end of the valve-ring V and from that chamber to the exhaust-port I.

The valve-ring V may be moved longitudinally over the hub portion H' by means of rods K, secured to the ring and extending out through the head B², where the outer ends are secured to a cross-bar M, which is connected with a hand-lever N, fulcrumed at u. (See Fig. 4.)

As illustrated in Fig. 1, the valve V is in position to admit steam to the pair of grooves $g g'$, from which it flows through passage f within the hubs, as indicated by dotted lines, to one of the ports e' in the disk D beneath the piston P. From thence the steam passes into the chamber l' in the lower part of the piston, then by a connecting-passage to the upper chamber n^4 , and out into the portion of the steam-chamber C below the piston, where the pressure exerted will cause the piston to move upward or in the direction indicated by the large arrow on the disk D—that is, the top of the disk will revolve in a direction opposite to that of the hands of a clock. As the disk D revolves the steam in the portion of the chamber C above the piston will exhaust into the piston-chamber n^3 , then by the connecting-passage to the lower chamber l^2 , thence through another steam-passage f' in the hubs (indicated by dotted lines) to a groove g' , and from there into the chamber O, and out at the exhaust-port I, all as indicated by the small arrows. The same operation will go on simultaneously through the piston opposite to the one in view in Fig. 1 and which is shown in section in Fig. 2. The position of the valve-ring V longitudinally of the hub H' will determine the time in the revolution of the hub when live steam will be cut off from the grooves $g g'$. With the ring V in the position shown steam will be cut off at about the time that the opening from the groove g to the passage f reaches the port v^2 , and at the same time the exhaust-steam may pass from the passage f' to the groove g' , which is open to the chamber O beyond the end of the valve-ring V. The rotation of the engine may be reversed by sliding the ring V inward until the ports $v^2 v^3$ open into the grooves $g' g'$, when live steam will be conducted to the piston P through the passage f' and exhausted through the passage f and

grooves g to the outer end of the chamber O . When the valve-ring V is in the middle of the chamber O —that is, with the port v^2 directly under the inlet E —steam will be cut off from all of the grooves in the hub H' and the engine will stop.

It will be observed that besides the novel construction of cut-off valve shown in the valve portion H' of the hub the sliding pistons themselves by their novel construction serve as cut-off valves, also as valves to change the flow of steam periodically from one side to the other of the revolving disk D , which divides the steam-chamber of the engine into 15 equal parts.

The hub H and the cylinder D' are provided with packing-rings $r\ r'$.

I claim—

1. In a rotary engine of the type in which the pistons while revolving around the engine-shaft reciprocate in a direction parallel with its axis, the combination of a revolving disk within the steam-chamber, a series of reciprocating pistons supported in the disk, each of which pistons is chambered to receive steam and act as a cut-off valve, and a pair of steam-ports for each piston within the disk which communicate with different chambers of the piston when it reciprocates.
2. In a rotary engine of the type described, a sinuous steam-chamber, a rotating cylinder which forms the peripheral limit of that chamber, a central disk web for the cylinder which equally divides the steam-chamber and is provided with steam-passages, a series of sliding chambered pistons supported in the web, which act as valves to admit steam to and exhaust steam from the steam-chamber upon opposite sides of each piston and upon

alternate sides of the web when the pistons 40 reciprocate.

3. In a rotary engine of the type described provided with reciprocating pistons in its steam-chamber, valve mechanism consisting of a cylinder concentric with the engine-shaft, 45 a pair of spiral-groove sections, in the periphery of the cylinder, for each piston, each of which pairs of spiral sections are respectively connected with a steam-passage leading to one of the pistons, a ring-valve upon the 50 grooved cylinder adapted to slide longitudinally thereof to admit steam to the grooves and regulate the cut-off therefrom.

4. In a rotary engine, a shaft portion exterior to the steam-chamber which is provided with two series of sections of peripheral spiral grooves and interior steam-passages connecting the grooves with the steam-chamber, and upon the grooved shaft portion a sliding valve with ports adapted to be adjusted to supply steam to either series of grooves and cut off the supply therefrom at any interval of each revolution, and to exhaust steam from the other series, or to close both series simultaneously. 55 60 65

5. In a rotary engine provided with one or more reciprocating pistons in its steam-chamber, antifriction-bearings for the pistons consisting of a series of balls in an endless passage upon the sides of each piston within the 70 walls of its supporting-groove, and with a portion of each passage open to one of such grooves, substantially as described.
